UNITED STATES PATENT OFFICE.

CARL R. KLOK, OF CHICAGO, ILLINOIS, ASSIGNOR, BY MESNE ASSIGNMENTS, TO UNITED TABLE-BED COMPANY, A CORPORATION OF ILLINOIS.

FOLDING BED.

1,270,528.

Specification of Letters Patent. Patented June 25, 1918.

Application filed March 31, 1913. Serial No. 757,784.

To all whom it may concern:

Be it known that I, CARL R. KLOK, a citizen of the United States of America, and resident of Chicago, Cook county, Illinois, 5 have invented a certain new and useful Improvement in Folding Beds, of which the following is a specification.

My invention relates to folding beds in general, but more particularly to those which 10 are combined with another piece of furniture, and especially beds of this kind which are combined with a table.

Generally stated, the object of my invention is to provide a novel and highly efficient 15 folding bed of the foregoing general character.

A special object is to provide a novel and efficient construction whereby the folding bed, with the mattress and bedding, is concealed 20 in the upper portion of the table body, which forms the head or foot of the bed when the latter is unfolded, and within which one end of the bed is supported in fixed position.

Another object is to provide a novel construction whereby the folding bed, with the mattress and bedding, is arranged to fold 25 into a concealed position below a table top disposed at a height suitable for a person seated in front thereof, and with clearance for the knees of said person below the bed, whereby the provision of the bed does not interfere in any way with the use of the structure as an ordinary library or writing 30 table, nor objectionably alter the shape or design thereof, so far as the appearance of being merely a table is concerned, it being understood that my object in this respect is to avoid as much as possible the use of anything 35 suggestive of the presence of a bed within the table.

It is also an object to provide certain details and features of construction tending to increase the general efficiency of a folding 40 bed of this particular character.

To these and other useful ends, my invention consists in matters hereinafter set forth and claimed.

In the accompanying drawings—

Figure 1 is a perspective of a bed table embodying the principles of my invention, showing the same folded and in use as a table.

Fig. 2 is a perspective of the same unfolded and in condition for use as a bed.

Fig. 3 is a transverse section of the table shown in Fig. 1, the section being taken between the ends of the table.

Fig. 4 is a similar view, but with the section taken on a line immediately inside of 60 the end of the table, whereby the bed mechanism is shown in elevation.

Fig. 5 is a fragmentary detail section on line 5—5 in Fig. 10, showing in section the end of the table which is shown cut off in 65 Fig. 10.

Fig. 6 is an enlarged fragmentary detail section view of a portion of the table top.

Fig. 7 is a section on line 7—7 in Fig. 6.

Fig. 8 is a plan of one side of the bed, 70 showing the same open, being a section on line 8—8 in Fig. 10.

Fig. 9 is an enlarged detail view of one of the joints of the bed frame.

Fig. 10 is a sectional view, showing the 75 bed unfolded.

Fig. 11 is a section on line 11—11 in Fig. 9.

As thus illustrated, my invention involves a table body A comprising fixed ends a, the fixed side a', the top sections a² and a³, the movable side a⁴, the fixed legs a⁵, and the connecting shelf a⁶, the design being that of an ordinary library or writing table. The section a² is provided on its under side with angle iron cleats a⁷ which are connected by 80 pivoted links a⁸ with the table body, whereby the table top and side a⁴ are foldable into the position shown in Figs. 2 and 10, the sections a² and a³ being hinged together so that the latter folds on top of the former, the side 85 a⁴ being hinged to fold against the inner surface of the section a³, when the latter is folded upon the other section of the top.

The folding bed B comprises a fixed section b secured to the ends a, and two folding 95 sections b' and b², the three sections being of angle iron and pivotally connected together by short sections b³ and b⁴, the relative formation of said sections preventing the bed frame thus formed from flexing 100 downward beyond a straight line, as shown in Figs. 2 and 10, but permitting the bed to be folded and practically rolled up in the manner shown in Figs. 3 and 4. The roll or bundle thus formed is above or higher than 105 the bed, obviously, so that the storage position of the bed is higher than the extended portion thereof when in use, and this extended position is in a plane approximately at the ordinary seating height, whereby the 110

bed-frame is capable of use as a seat when unfolded but not when folded. The length of the bundle is, of course, the same as the width of the bed, but the width of the bundle 5 is only approximately one-third of the length of the bed. A metallic fabric b^5 is stretched on the frame thus provided, and legs b^6 and b^7 are pivoted on the sections b' and b^2 , respectively, the legs b^6 having their upper 10 ends connected by the pivoted links b^8 with the sections b^8 , and the upper ends of the legs b^7 being connected by the pivoted links b^9 with the sections b^4 , whereby the legs automatically fold upon the sides of the bed 15 frame when the latter is folded, in the manner shown in Fig. 4. The legs b^6 are connected by a bar b^{10} , and the legs b^7 are connected by a bar b^{11} , which bars rest on the sections b' and b^2 when the bed is folded 20 within the table. The sections b^3 and b^4 serve to space the sections b , b' and b^2 apart sufficiently to give room for the bedding, a mattress C being employed on the said metallic fabric.

25 With the foregoing construction I am enabled to provide a table bed in which the bottom of the bed is high enough to provide knee clearance below, without raising the top of the table higher than is proper 30 for a person sitting in front thereof. The table does not, in appearance, depart materially from the usual and ordinary designs, and is intended to conceal the bed without the necessity of employing features of construction 35 which would tend to make the structure look like something more than an ordinary library or writing table; and, as stated, the use of the table is not in any way interfered with, as it has the requisite 40 knee space below the bottom of the bed, and is, at the same time, not higher than is permissible for a writing or reading table, which is broadly new with me, so far as I am now aware.

45 To keep the frame from spreading, the sections b^3 are connected by a swiveled bar D, provided with pivots d , and the sections b^4 are connected by a similar bar E, both bars being dropped at the middle to give 50 clearance for the fabric. The links or sections b^8 are pivoted at d' and d^2 , to and inside of the sections b and b' , and the sections b^4 are similar.

The front side a^4 has end portions F which 55 are sections of the front table-legs and which rest on shoulders f on the legs a^5 , when the bed is folded and the top is down, which portions preserve the continuity of the legs, and appear to be a part thereof. Also, it 60 will be seen that the angle bars used in the construction of the sections of the bed frame have upstanding vertical flanges (see Figs. 9 and 11) and that the mattress is disposed between these flanges, the metal fabric being secured to the lower or horizontal flanges 65

of these angle bar sections. Furthermore, the short sections b^3 and b^4 are disposed inside the upstanding flanges of the other sections, and in this way the frame will fold upwardly but not downwardly, being held 70 rigidly in a horizontal plane by its own stiffness, because of the overlapping of the short sections on the long sections. With the vertical flanges of the sections extending toward each other when the frame is folded, 75 a bundle of less thickness or height is obtained than would be the case with the said angle bars turned over, as in the latter case the flanges would extend downward and upward beyond the top and bottom surfaces 80 of said bundles, and thus take up more room in the table.

As stated, the head section of the bed frame is fixed in the table body, and with the arrangement shown it is also held absolutely against movement relative to said table body; but I do not limit myself to the particular construction shown and described, as various changes may be made, obviously, without departing from the spirit 90 of my invention. As shown, the legs a^5 are cut away inside the body to form shoulders G for the ends of the strips g which form the lower portions of the end walls a of the body. The frame section b is rigidly secured to these strips, and thus clearance is provided inside the body for the legs of the bed-frame. With this arrangement the two end sections b and b^2 are always right side up whether the bed is folded or unfolded. 95 The section b supports the entire bed frame within the table body.

From the foregoing it will be seen that in a practical table-bed embodying the principles of my invention, the bed frame must 105 fold over twice in order to get the same into a table of ordinary proportions, such as an oblong library table, and in order to have the table and bed stand at right angles to each other, whereby the length of the table 110 and not the width thereof determines the width of the bed. It being also essential that as few folding operations be involved as possible, one end section of the frame is preferably fixed in the table body, whereby the 115 sections b and b^2 of the bed frame are both right side up whether the bed is folded or unfolded. In order to properly support the bed within the table-body, and in order to provide clearance for the folding legs b^6 and b^7 and their controlling links b^8 and b^9 , the table legs a^5 are recessed inside the body to 120 form shoulders G, and spacing strips or side strips g are secured to the sides of the bed frame and supported upon these shoulders, 125 these strips being in effect a part of the end walls of the table body. With this construction and arrangement, the bed frame folds over twice in order to reduce to the proper size for inclosure in the table body, but these 130

are the only folding operations involved, so far as the bed frame itself is concerned, inasmuch as this frame is not disturbed or moved again after the second folding operation which brings the section b^2 right side up within the table.

- With the construction shown and described, the intermediate or middle section b' of the bed-frame is left free and clear 10 at the sides thereof whereby this section is available for use as a seat in entering and leaving the bed in the ordinary and natural manner, which is an important and essential requirement for a perfect bed. This, it will 15 be seen, is because the end-walls a extend only to the joint between the fixed head-section b and the folding middle section b' , whereby the desired clearance is afforded at both sides of the middle section of the bed. 20 Furthermore, it will be seen that the bed-frame is foldable while the head-section b remains in fixed and stationary position, whereby the folding and unfolding of the three-section bed-frame is accomplished in 25 the desired manner and for the purpose described in a structure in which one end-section always remains at a fixed height from the floor. Again, it will be seen that the swiveled cross-bar D not only connects to- 30 gether the two sides of the foldable portion of the bed-frame, but also serves through the medium of said frame to hold the front ends of the end-walls a a fixed distance apart, the table-body thus depending and relying 35 for its rigidity to a considerable extent upon the stiffness and rigidity of the bed-frame. 40 By maintaining the frame section b permanently right-side-up, so that it is never turned up-side-down, the structure becomes an article of furniture, in this case a library table, when the rectangular bundle composed of three superimposed layers, and with its top still uppermost, is inclosed 45 therein. In other words, the immediate re- sult, or practically so, of the inclosure of the three-layer bundle in a position right-side-up within the bed structure is a table. The flexible mattress support, such as the metal fabric b^5 , extends over the mattress 50 at the top of the rectangular bundle which is constructed from the head and foot and middle sections of the frame and when the bundle is thus inclosed with its said top uppermost the structure becomes a useful 55 article of furniture, preferably a table.
- It will be seen that the bed-frame B is structurally distinct from the table-body A, the said body being in itself a complete article of furniture. In other words, the 60 said bed-frame could be omitted, and still the body A could have the shape and construction essential for a table. Of course, the bed-frame when fastened inside of the table contributes some strength thereto, especially across the front of the table through

the medium of the spreader D, but notwithstanding this the table-body is practically complete in itself and has the form and appearance of a complete table, even should the angle-iron bed-frame be omitted. Fur- 70 thermore, being a table, the said body A is of a shape and construction to preclude the use of the structure as a seat except when the frame is unfolded. When the bed-frame is unfolded, the middle section thereof 75 is then available at opposite sides as a seat, but when the bed is folded the structure formed by the bed-frame and table-body is then, of course, incapable of use either as a bed or a seat—that is to say, the structure 80 resulting from the folding of the bed is neither designed nor adapted nor intended for use either as a bed or seat. Again, it will be seen that the combinations and constructions employed make it possible to have 85 the bed-frame, when unfolded, disposed at a proper height, which is ordinarily called sitting height, being about the same height as an ordinary chair or couch; and this is accomplished without in any way interfer- 90 ing with or detracting from the essential requirements of the article of furniture which the structure becomes when the bed is folded. In other words, by the combinations and constructions employed, the bed-frame is a 95 proper and satisfactory height from the floor, both when folded and unfolded, inasmuch as for table purposes the top of the bed frame is permissibly and desirably higher when in folded condition, and is de- 100 sirable lower when unfolded and in use as a bed or seat. Thus neither purpose con- flicts with the other, and the frame folds and unfolds in a way that brings about a 105 satisfactory result in each case, notwithstanding that one section of the bed-frame is maintained right side up at a fixed height from the floor and is thereby held stationary during the folding and unfolding of the frame. 110

Obviously, therefore, my invention should not be confused or confounded with so-called davenports, or with divans and sofa beds, for my invention is entirely different from these things, and is not adapted for any such 115 purpose, inasmuch as my invention contem- pletes a method of mounting and operating a three-section bed-frame, having links or short sections between the three long sec- tions, which entirely precludes the use of the 120 structure as a seat when the bed is folded. For with the method shown and described, and in order to have a bed of correct height, the bed-frame is necessarily higher when folded than when unfolded, and when thus 125 folded is much too high for use as a seat. But at this height the folded frame is at just the right height for the top portion of a table, or of any structure or article of fur- niture which is necessarily or desirably 130

higher when the bed-frame is folded and fully inclosed than when the bed is in use—that is to say, in which the bed-frame itself is desirably or permissibly higher when 5 folded than when unfolded.

The transversely folding bed-frame B has the third section thereof disposed permanently right-side-up at sufficient height for a mattress which is thin enough to fold with 10 the frame. By this is meant, of course, that the permanently right-side-up section of the frame is supported in such position that the frame will be amply high enough with a comparatively thin and flexible mattress, and 15 will not be too low for a bed. Thus, the third section of the frame, although held in fixed position, is exactly or substantially at the right height for both purposes, as it is high enough to give the required clearance below 20 when the structure is in use as a table, and is also high enough to provide a bed practically of standard or of the ordinary height when employed with a comparatively thin mattress which will fold up readily with 25 the frame.

It will also be seen that with the construction shown and described, involving a bed-frame composed of three sections, with links or short sections between, the table can 30 be of door-width size, so that it can be easily pushed through an ordinary doorway.

What I claim as my invention is:—

1. A folding bed comprising a body which in itself is a complete article of furniture, 35 a three-section transversely folding bed-frame whereof the inner end-section is always right-side-up and horizontal, having devices intermediate the head and foot of the bed to connect the sections together, 40 means on said body to support the said permanently right-side-up inner end-section a fixed height from the floor, serving to hold the inner end-section stationary within said body while the other sections are being folded thereon to bring the outer end-section right-side-up below the inverted middle section, folding legs coöperating with said body to support the frame at a height which will be sufficient for a bed of ordinary height 45 50 with a mattress of a thickness to fold readily with the frame, the middle section being entirely outside of said body when the bed is unfolded, thereby to permit use of said middle section as a seat for entering and leaving the bed, and means on said frame to support the mattress, said sections being each approximately one-third the length of the bed, the outer end-section and the middle section being supported entirely by and horizontally above said inner end-section when the bed is folded, and said body being of a shape and construction to preclude use thereof either as a bed or a seat when the sections are folded together and having means 60 65 to entirely conceal the bed frame therein.

2. A table-bed comprising an oblong and rectangular table-body which in itself is a complete article of furniture, having side and end and top walls and fixed legs at the four corners thereof, forming a chamber 70 which is open at the bottom, a three-section folding bed-frame, the sections being each approximately one-third the length of the bed, having devices to connect the sections together, means on said end walls to support 75 the head-section in fixed position at the open bottom of said chamber, legs for the middle and foot sections, foldable with said frame and a mattress to a concealed position within said chamber, means on said frame to support the mattress, said end-walls extending only to the joint between the head-section and the middle section, thereby to permit use of said middle section as a seat for entering and leaving the bed, said foot-section 80 being supported entirely by and horizontally above said head-section when said body is in use as a table, said top-wall and the front side-wall being movable to permit unfolding of the bed, and a member on the 85 foldable portion of said frame to connect the sides thereof and thereby hold the front ends of said end-walls a fixed distance apart, said member being disposed outside of said body while the bed frame is unfolded and 90 immediately inside of said front-wall when the table is closed.

3. In an article of furniture of the class described, a table embodying a single side wall and end walls connected to and extending at right-angles therefrom, thereby leaving one side of the table open, a sectional folding bed-frame having one section thereof fixed to said end walls against vertical movement, and a member on a section of 105 said bed-frame which lies outside the table body when the bed-frame is unfolded and inside the table body when the bed-frame is folded thereinto, and in each position 110 serves to connect the free ends of said end walls together and thus prevent spreading thereof.

4. In a folding bed, the combination of (1) a bed-frame provided with a flexible mattress support, said frame including end and intermediate sections, the end sections forming the head and foot of the bed, and all of the sections being pivotally connected to fold together and form with the mattress and bedding a rectangular bundle consisting of a flattened roll wherein one end section is disposed between an intermediate section and the other end section, with the sides of the bed forming the ends of the roll, so that said bundle in length is substantially 115 the same as the transverse dimension of the bed and in width is approximately one-third 120 of the length of the bed, whereby the head and foot and middle sections are brought together and superimposed in substantially 125 130

- horizontal layers by the folding of said frame, and with a portion of said flexible support overlying the mattress at the top of said bundle; (2) a structure for supporting and inclosing said bundle for storage therein, adapted to prevent use of said frame as a seat except when the sections thereof are unfolded, having means for maintaining one of said sections permanently right-side-up for a mattress thin enough to fold with the frame and to receive thereon the other sections and form the lower portion of said bundle when the bed is completely folded, thereby to sustain the entire weight of said bundle at the bottom thereof, and also to support a portion of the bed when said frame is unfolded, serving to hold said one section horizontal during the unfolding of the other sections, said structure in itself forming an article of furniture which precludes use thereof either as a bed or a seat when said three-layer bundle with its said top uppermost is finally inclosed therein; and (3) folding legs for said bed-frame, cooperating with said means to support the bed-frame in a plane lower than the storage position of said bundle and approximately at the ordinary seating height when the bed is in position for use.
5. In an article of furniture of the class described, a table embodying a rigid side wall and end walls connected to and extending at right-angles therefrom and having a movable top and side wall, thereby leaving one side of the table open, a sectional transversely folding bed-frame supported by said table and connected to said end walls, adapted to fold and unfold through the open side of the table when the top is open, and a member on a folding section of said bed-frame to connect together the sides of the frame and hold the front ends of said end walls a fixed distance apart, said frame and member when entirely folded being concealed when the table is closed. 45
6. The folding bed structure, as set forth in claim 4, in which said permanently right-side-up section is held at a fixed height sufficient for an ordinary bed, and in which said legs fold automatically into position above 50 said permanently right-side-up section to form part of the ends of said bundle.
7. The folding bed structure, as set forth in claim 4, in which said frame has a transverse spreader on the folding portion thereof 55 in position to partly form the front of said bundle, and said structure having a rectangular table top and fixed legs at the four corners thereof, the front table legs being unconnected across the front of the 60 table when said frame is unfolded except through the medium of said spreader which is then immediately outside of said table.
8. The folding bed structure, as set forth in claim 4, in which said permanently right-side-up section forms one end of the frame, and said article of furniture being of a size and shape to permit use of the middle section of the frame as a seat in entering and leaving the bed. 65
9. The folding bed structure, as set forth in claim 4, in which said permanently right-side-up section is rigidly secured and fixed against movement in said structure, and said article of furniture being of a size and 70 shape to contain said bundle and permit use of either side of the middle section of said frame as a seat when the bed is unfolded.
- Signed by me at Chicago, Cook county, Illinois, this 27th day of March, 1913.
- CARL R. KLOK.

Certificate of Correction.

It is hereby certified that the State of incorporation of the assignee in Letters Patent No. 1,270,528, granted June 25, 1918, upon the application of Carl R. Klok, of Chicago, Illinois, for an improvement in "Folding Beds," was erroneously given as "Illinois," whereas said State should have been given as *Virginia*, as shown by the records of assignments in this office; and that the said Letters Patent should be read with this correction therein that the same may conform to the record of the case in the Patent Office.

Signed and sealed this 30th day of October, A. D., 1923.

[SEAL.]

KARL FENNING,
Acting Commissioner of Patents.
